RAILWAY CAR AIR CONDITIONING SYSTEM

Horace L. Smith, Jr., Richmond, Va., assignor to
Thermal Engineering Corporation, Richmond,
Va., a corporation of Virginia

Application August 17, 1935, Serial No. 36,635

4 Claims. (Cl. 62—117)

This invention relates to air conditioning and more particularly concerns an improved air conditioning system for use on railway passenger cars of steam roads.

5 The provision of conditioned air in railway passenger cars involves generally two conflicting problems; that of maintaining comfortable conditions and that of economy. The power available on steam trains for the operation of auxiliary equipment, such as air conditioning apparatus, is quite limited. On the other hand, passenger cars are necessarily subjected to widely varying temperature conditions in the course of an average run and comfortable atmospheric conditions can 10 be maintained therein only if a very flexible system of relatively large cooling capacity is provided.

In the past, railway car air conditioning systems have been a compromise between two desired ends, the maintenance of comfortable conditions and reasonably economical operation. Known systems operated in whole or in part by electricity involve a high initial cost and high operating expense due to their low efficiency. 20 Thus when such systems are installed on a railway car, it is necessary to replace the usual car lighting generator and battery with electrical generating and accumulating equipment of greatly increased capacity and this replacement 25 materially increases the initial cost of the installation. The energy for operating electrically driven systems is delivered from the locomotive through the draw bars, the axle driven generator, the storage battery and the electric motors to the 30 refrigerating apparatus, and consequently, the overall efficiency of the system is low and the operating cost correspondingly high.

Steam operated railway car air conditioning systems employing steam jet vacuum boosters 35 have been used to a certain extent, and in general, are more economical to install and operate than electrically driven systems. However, such systems operate effectively under maximum steam supply only, since the efficiency of a steam jet or 40 injector in creating a vacuum falls rapidly as the steam pressure on the jet is reduced, and as a practical matter, effective cooling can be obtained only if the steam is supplied continuously at the rated pressure. The piping available for 45 supplying steam to the various car carried units of a train is limited in size, and when a large number of car units are in operation, the steam pressure falls off in the rearward cars and wasteful operation and insufficient car cooling results.

50 In both the electrically driven and steam op-

erated systems now in use, the control is intermittent, the apparatus operating at maximum capacity whenever it is turned on. Since the system must have sufficient capacity to properly cool the car under the most adverse outside 5 temperature conditions met with in operation, the intermittent control produces undesirably wide fluctuations in car temperature under moderate outdoor conditions, and further results in lowered efficiency due to the power losses involved in 10 starting the apparatus at frequent intervals.

With the above and other considerations in mind, it is proposed in accordance with the present invention to provide an improved railway car air conditioning system for steam trains which 15 is controlled in an efficient and economical manner by varying the cooling effect in accordance with the heat load imposed whereby the car air temperature is maintained at the desired value without wide fluctuations. Other objects of the 20 invention include a system of this nature which is small and compact, inexpensive to install and low in operating cost. A further feature of the invention involves the provision of improved and simplified means for operating the system when 25 the railway car is standing in a yard or station with no locomotive connected thereto whereby a car may be precooled before it is connected in a train and occupied by passengers.

In general, the above and other objects of the 30 invention are carried out by providing a compression type refrigerating system to cool the car and driving this system with a steam prime mover capable of efficient operation over a wide range of speeds. In accordance with the invention, the speed of the prime mover and hence the 35 speed of the refrigerant compressor is varied by means responsive to atmospheric conditions in the car, and in this manner, the car temperature is maintained constant at the desired value 40 and a very high operating efficiency is obtained. I have found that a reciprocating steam engine of the uniflow type is particularly adapted for use in my improved system.

The speed control is conveniently accomplished 45 by adjustment of the steam supply to the prime mover and to this end, I preferably provide means responsive to both the speed of the prime mover and the temperature of the car, whereby the compressor operates at a speed which is maintained 50 constant in spite of steam pressure variations or variable load factors so long as the car temperature is within the desired range, but which speed is varied to compensate for departures from the desired car temperature conditions.

The refrigerant compressor is a constant volume device, acting on a relatively dense gas, and accordingly, the compressor efficiency increases as its speed drops. High compressor speeds result in high gas velocities and high friction losses. There is, of course, a low limit to the speed at which it is economical to operate a refrigerant compressor since the relation between the initial investment and required capacity must be taken into account. However, since heat load conditions vary widely and operation is for the most part well below maximum capacity, I obtain a considerable increase in efficiency by varying the compressor speed in accordance with load requirements since in this manner, the compressor always operates at the highest efficiency obtainable for the load imposed and further, losses resulting from frequent starts are avoided.

My improved variable speed steam driven system is better suited for use with steam supply facilities of multiple car trains than previously known systems. With known steam systems, which are governed by a full-on or full-off control, the units on the several cars of a train frequently operate simultaneously and the rapid steam consumption by the forward car units so far reduces the steam pressure on the rearward car units that these units operate very inefficiently and usually fail to produce the required cooling effect until after the forward car units have stopped operating. With my improved variable speed steam system, the amount of steam drawn from the train line by each unit is throttled to the minimum value which will maintain the desired car temperature under continuous operation, and sudden fluctuations of train line steam pressure with resultant inefficient or inadequate operation of the rearward car units is avoided.

In accordance with one embodiment of my invention, I provide an over-running clutch or equivalent means in the driving connection between the steam engine and the refrigerant compressor, and further provide an electric compressor driving motor which may be readily connected directly to drive the compressor independently of the steam engine. With this arrangement, the car may be pre-cooled by merely connecting the electric motor to the refrigerant compressor and supplying current from a track-side outlet, the steam engine remaining stationary during such operation because of the over-running clutch in its driving connection.

In describing the invention in detail, reference will be made to the accompanying drawings in which:

Figure 1 is a plan view of a car carried refrigerating unit embodying the invention;

Figure 2 is a side elevation of the unit shown in Figure 1;

Figure 3 is an end elevation of the car carried unit;

Figure 4 is an enlarged detailed view, partly in section, of the compressor driving mechanism;

Figure 5 is a sectional view of the governor mechanism;

Figure 6 is a sectional elevation of a railway passenger car equipped with an air conditioning system embodying the invention; and

Figure 7 is a diagrammatic view of a train of passenger cars equipped with systems embodying the invention.

Referring to the drawings, my improved railway car air conditioning system has been shown as applied to a railway passenger car of conven-

tional construction which has been diagrammatically illustrated at P in Figures 6 and 7. The system is of the type in which a refrigerant from a refrigerating unit, or a suitable heat transfer medium cooled by such refrigerant, is circulated in heat exchanging relation with air supplied to or circulated in the car. The particular form of car cooling coil and air propelling means forms no part of the invention and various forms of apparatus may be employed for this purpose. In the embodiment shown in Figure 6, fresh air from outside of the car is drawn by a fan 2 through one or more intake openings 3 into a chamber 4 located above the ceiling of the car vestibule 7, and is propelled by the fan through a duct 5 to suitably placed ceiling outlets 6 in the car. A cooling coil 8 is located in the chamber 4 in heat exchanging relation with the air drawn therethrough and this coil is at times supplied with refrigerant or other cooling fluid from a refrigerating unit hereinafter described. The fan 2 may be operated by an electric motor, as shown. The fan and motor may be of relatively small capacity and may replace the usual electric fans customarily installed in railway passenger cars. Air may be discharged from the car through the doors, windows or other air pervious openings thereof, or special air outlet ducts may be provided, if desired.

The refrigerant for cooling the air delivered to the car is supplied by a refrigerating unit carried beneath the car in a housing generally designated H. The housing may take any suitable form and is preferably disposed beneath the car frame and between the center line of the car and the clearance limits at one side thereof, as shown in Figure 3.

The refrigerating unit proper comprises generally a mechanical refrigerant compressor 10, preferably of the reciprocating type, a refrigerant condenser C and suitable means such as the fans 11 and 12 for drawing a current of cooling air over the condenser surfaces. The intake 13 of the compressor 10 is connected to draw refrigerant gas from the car coil 8 by a pipe 14, preferably provided with a cut-off valve 15. The discharge 16 of the compressor 10 is connected through a pipe 17 and a valve 18 to the condenser C. The outlet of the condenser C passes through a cut-off valve 19 and a pipe 20 to the car cooling coil 8, the proper condenser pressure being maintained by a suitable expansion valve 21. The condenser may take any suitable form and preferably includes finned coils or passages 22 communicating with a liquid refrigerant accumulator 23.

The condenser cooling fans 11 and 12 are disposed in suitable circular openings in a shield 24 extending across the inner face of the condenser C, and air drawn through the condenser passes laterally through the housing H and out through the louvers 25 in its outer wall. The fans 11 and 12 are journaled in suitable brackets 26 and 27 and are driven by a single shaft 28 through suitable spiral gears 29 and 30.

The refrigerant compressor 10 is driven by a steam prime mover, which preferably comprises a direct connected reciprocating steam engine of the uniflow type, which is illustrated at E. In general, the steam prime mover employed should be capable of efficient operation over a wide range of speeds, and I have found the uniflow type of steam engine admirably suited to this purpose. The crank shaft 31 of the engine E is connected to the compressor shaft 32 through an over-

running clutch or equivalent means 33. As shown in Figure 4, this clutch may take the form of an inner element 34 connected to the engine shaft 31 and having a plurality of cam recesses 35 there-
 5 in carrying balls or rollers 36 and surrounded by an outer element 37 fixed to the compressor shaft 32. As will be understood, rotation of the inner element 34 by the engine E in a counterclockwise direction, as viewed in Figure 4, causes the rollers 36 to lock in the cam recesses 35 and so form a driving connection between the engine and the compressor. If the outer element 37 is driven independently of the engine E, the rollers 36 are released and the engine remains stationary.
 10 15 I prefer to provide an electric motor for operating the compressor 10 independently of the engine E when the car carrying the system is not coupled to a locomotive whereby the car may be precooled before it is occupied by passengers. To this end, a motor 38 is provided, having a friction wheel 39 on its shaft disposed parallel to the outer member 37 of the over-running clutch. A friction idler 40 is slidably carried by a suitable bracket 41 and is movable to and from a position 20 to simultaneously engage and form a driving connection between the motor friction wheel 39 and the outer clutch member 37. The idler 40 may be operated in any suitable manner, and as shown, a pneumatic diaphragm mechanism 42 is pro-
 25 vided for this purpose. This mechanism includes a diaphragm 43 acting against a spring 44 and operating a plunger 45 connected to the sliding journal 46 of the idler 40. Compressed air from a suitable source is supplied to the mechanism 35 42 through a pipe 47 under the control of a man-
 30 ual three-way valve 48. When the valve 48 is manipulated to admit air pressure to the dia-
 35 phragm 43, the idler is moved to engage the wheel 39 and clutch member 37, thus establishing a 40 driving connection between the motor 38 and the compressor 10. When the valve 48 is manipulated to cut off the air supply and discharge air from the diaphragm chamber of the mechanism 42, the spring 44 moves the idler 40 out of engagement 45 with the friction wheel 39 and clutch member 37, thus breaking the driving connection.

The fan operating shaft 28 is driven with the compressor 10 through a driving connection comprising the aligned pulleys 58 and 59 and the belts 60 engaging these pulleys. The desired belt tension is maintained by an idler 61 engaging the lower span of the belts 60 and pressed against the belts by a spring 62 which is tensioned between a fixed support and the pivoted idler carrying arm 55 63.

Steam for operating the engine E is supplied from the locomotive 50 through the usual train steam line 51 and a branch pipe 52 leading to each car carried unit. The steam passes through 60 a manual supply valve 53, a water separator 54, an automatic cut-off valve 55 and a throttle valve 56 to the engine E. Exhaust steam from the engine E passes out of the housing H through the pipe 57.

65 During operation of the system, the supply of steam to the engine E is automatically governed by means jointly responsive to the engine speed and the temperature of the air in the car. In the disclosed embodiment, this is accomplished 70 by providing a speed responsive governor G connected to operate the steam engine throttle valve 56, and by modifying the action of the governor in accordance with changes in car temperature.

75 Any suitable form of speed governor may be used. The governor G disclosed is mounted on

the frame of the engine E and driven from the engine shaft through suitable gearing, not shown. The governor has two centrifugally operated weighted elements 64, pivotally supported on a cross piece 65 fixed to the governor shaft 66. A 5 sliding collar 67 carried by the shaft 66 is moved along this shaft by the outward movement of the centrifugal elements 64, and the movement of the collar 67 is transmitted to a shaft 68 by the arm 69. The shaft 68 carries an arm 70 outside of the governor casing, and a tensioned spring 71 connected to this arm exerts a force thereon which opposes the outward movement of the centrifugal elements 64. The end of the spring 71 is connected to a pivoted lever 72, the movement 10 of which varies the force exerted by the spring 71 on the lever 70, as is apparent from the showing in Figure 2. A second arm 73 is connected to the shaft 68 of the governor G and is in turn connected through the links 74, 75, 76 and 77 15 to the stem of the steam engine throttle valve 56. Suitable means are provided for moving the lever 72 and so varying the tension of the governor spring 71 in accordance with changes in air temperature within the car P. In the disclosed embodiment, this is accomplished by means of a pneumatic diaphragm mechanism 78 having a flexible diaphragm 79 connected to the lever 72 through a plunger 80. The downward movement of the diaphragm 79 and plunger 80 20 is opposed by a spring 81 and compressed air from a source indicated by the pipe 83 is supplied to the upper surface of the diaphragm 79 through a pipe 84 under the control of a thermostat 82 in the car. The thermostat 82 is of 25 known construction and acts to reduce the air pressure on the diaphragm 79 as the car air temperature rises above a predetermined value, and to increase this air pressure as the car air temperature falls below the predetermined value. 30 35 40

In the position shown in Figure 2, it is assumed that the car air temperature is above the desired value, and accordingly, a low air pressure is applied to the diaphragm 79 and the spring 81 has lifted the plunger 80 and moved 45 the lever 72 to its highest position against a stop 85, placing the governor spring 71 under maximum tension. In this condition, the centrifugal elements 64 of the governor are moved 50 inward, turning the shaft 68 in a clockwise direction as viewed in Figure 2 to a point where the throttle valve 56 is opened to a considerable extent, and the engine E and compressor 10 operate at a comparatively high speed which is limited and controlled by the governor G. The 55 high speed operation of the refrigerating system reduces the car air temperature and when this temperature falls to a predetermined value near the minimum comfortable temperature, the increase in air pressure on the diaphragm 79 moves 60 the plunger 80 and lever 72 to their lowest positions, reducing the tension on the spring 71 to the minimum value. The centrifugal elements 64 of the governor accordingly move outward, turning the governor shaft 68 in a counter- 65 clockwise direction and so closing the throttle valve 56 to a point where the engine and compressor operate at minimum speed. If, under these conditions, the heat load in the car is so light that even at minimum speed operation the 70 refrigerating system lowers the car temperature to the minimum desired value, then the resultant further increase in control air pressure acts through the pneumatic steam valve 55 to cut off the steam supply to the engine E and so stop 75

the refrigerating system. The operating mechanism of the valve 55 is of the pneumatic diaphragm type described above, and air pressure is supplied thereto from the thermostat pipe 84 5 through the pipe 86, as shown in Figure 2.

As the car air temperature increases from the minimum value, the reduction in the air pressure controlled by the thermostat 82 first opens the automatic pneumatic steam valve 55 and so 10 starts the engine E and compressor 10 at minimum speed. A further rise in car temperature further reduces the control air pressure and the diaphragm 79 of the mechanism 78 is lifted by the spring 81, thus lifting the lever 72 and increasing the tension on the governor spring 71. This increased governor spring tension moves the centrifugal elements 64 inward, turning the shaft 68 in a clockwise direction and opening the throttle valve 56 to admit more steam and so 15 increase the speed of the engine E and compressor 10.

Although in the foregoing description, the operation of the control equipment from maximum to minimum speed has been described, it 25 will be understood that under normal conditions, that is, a continuing heat load on the car, the system will operate continuously at some intermediate speed, the governor G maintaining the speed constant at a value determined by the 30 temperature in the car, and the thermostat altering this speed, as required to compensate for changes in car temperature.

From the above description, it will be seen that the governor G and its thermostatic control act to vary the operating speed of the refrigerating system in accordance with changes in the heat load conditions in the car. As long as the car temperature remains constant at the desired value, the governor maintains the compressor speed constant but any change in car 35 temperature produces a corresponding change in compressor speed which counteracts and corrects the car temperature change. With this arrangement, the compressor operates continuously so long as cooling is required, and further operates at all times at the lowest possible speed which will maintain comfortable car conditions under the heat load imposed. Since the compressor efficiency rises as its speed is reduced, the 40 system operates very efficiently and further, since the refrigerating system operates continuously while cooling is required, the losses involved in starting the compressor are avoided. By the use of the system disclosed, dependable cooling can 45 be obtained in all of the cars of long trains. Due to the throttled operation of car cooling units, sudden drops in train line steam pressure are avoided and the operation of forward car units does not reduce the steam pressure available on rearward cars to a point where inadequate 50 cooling results. Differences in train steam line pressure are automatically compensated for by the speed governors of the various car units and accordingly it is unnecessary to manually 55 change the adjustment of car equipment in accordance with the position of the car in a train.

I claim:

1. A railway car air conditioning system comprising a car carried refrigerating unit includ-

ing a mechanical refrigerant compressor, means connected to said refrigerating unit for cooling the interior of a railway car, a variable speed steam engine connected to drive said compressor, means responsive to both the temperature in said car and the speed of said engine for variably controlling the supply of steam to said engine and means responsive to a minimum car temperature for cutting off the supply of steam to said engine independently of the action of said means responsive to both car temperature and engine speed.

2. A railway car air conditioning system comprising a car carried refrigerating unit including a mechanical refrigerant compressor, means connected to said refrigerating unit for cooling the interior of a railway car, a variable speed steam engine connected to drive said compressor, a speed responsive device driven by said steam engine comprising means moved by centrifugal force acting against a spring, means for variably controlling the rate of supply of steam to said engine in accordance with the movement of said centrifugally operated means, means responsive to the temperature in said car for varying the force of said spring and further means responsive to the temperature in said car for cutting off the supply of steam to said engine when the car temperature reaches a minimum value.

3. A railway car air conditioning system comprising a car carried refrigerating unit including a mechanical refrigerant compressor, means connected to said refrigerating unit for cooling the interior of a railway car, a variable speed steam engine connected to drive said compressor, a speed responsive device driven by said steam engine comprising means moved by centrifugal force acting against a spring, means for variably controlling the rate of supply of steam to said engine in accordance with the movement of said centrifugally operated means, and means responsive to the temperature in said car for varying the force of said spring.

4. In a railway car air conditioning system, in combination with a steam locomotive and a plurality of cars connected thereto, a train steam line arranged to be supplied with steam from said locomotive and having a connection extending to each of said cars, a refrigerating unit carried by each car and including a mechanical refrigerant compressor, each refrigerating unit being arranged to cool the interior of the car associated therewith, a variable-speed steam engine on each of said cars for driving the refrigerant compressor thereon, means for supplying steam from said connections to the steam engines on said cars, means on each of said cars responsive to both temperature in such car and the speed of the steam engine thereon for variably controlling the supply of steam from the associated connection to said engine, whereby a sufficient amount of steam is supplied to each engine, independently of the operation of other engines, to operate its associated compressor in accordance with the cooling requirements of the associated car, and means on each of said cars responsive to a minimum car temperature for cutting off the supply of steam to the engine.

HORACE L. SMITH, JR.
